UNITED STATES PATENT OFFICE.

WALLACE SUMNER GRANGE, OF MALTA, ILLINOIS.

BOOKCASE.

SPECIFICATION forming part of Letters Patent No. 625,103, dated May 16, 1899.

Application filed January 6, 1898. Serial No. 665,823. (No model.)

To all whom it may concern:

Be it known that I, WALLACE SUMNER GRANGE, a citizen of the United States, residing at Malta, in the county of De Kalb and

5 State of Illinois, have invented certain new and useful Improvements in Bookcases; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to bookcases; and it has for its object to provide a simple and efficient construction of bookcase having a series of separable box-like compartments adapted to rest one on top of the other with 20 the open side of each compartment to the front of the case, the lower side of each compartment when in position constituting the shelf for the support of the books and the several compartments when separated, constituting 25 boxes for the shipment or transportation of the books, thus obviating the necessity of removing the books from the case when their shipment or transportation is necessary.

30 To the accomplishment of the foregoing and such other objects as may hereinafter appear, the invention consists in the construction and the combination of parts hereinafter particularly described and then sought to be specifically defined by the claims, reference being had to the accompanying drawings, forming a part hereof, and in which—

Figure 1 is a perspective of a bookcase constructed according to my invention, the top 40 and one side being separated from the other parts for clearness of illustration. Fig. 2 is a vertical cross-section through a bookcase, and Fig. 3 is a sectional view through a portion of the top and one side to show clearly 45 the groove or recess for receiving the ends of the side members.

In the drawings the numeral 1 designates a series of box-like compartments placed one on top of the other, so as to constitute a series 50 of shelves for supporting the books. To the front edge of one of the horizontal sides of each compartment—for instance, to the

front edge of the lower horizontal side of each compartment—is secured or formed a flange 2, adapted to extend across the joint between 55 the bottom of one compartment and the top of the compartment next below, so as to close the joint and conceal the same from view, thus giving the appearance of a series of permanently-secured shelves. These flanges also 60 prevent one compartment from sliding back of the front edge of the next compartment in contact therewith.

The numeral 3 designates the sides of the bookcase, which are separable from the box-like compartments and which extend at the top above the upper horizontal side of the top compartment and at the bottom below the lower horizontal side of the bottom compartment, so as to constitute tongues, which 70 will enter grooves or recesses formed at the ends of the top or cover to the bookcase and also to the bottom or base of the bookcase, respectively.

The top or cover of the bookcase is designated by the numeral 4, and it is provided at 75 its front with a flange or molding 5 to extend down over the top of the uppermost compartment, so as to conceal the front edge thereof and form an ornamental finish. It is provided 80 at opposite ends with projecting and depending plates 6, which preferably are made of metal and of any ornamental configuration or design and color. These plates form grooves or recesses 7 at opposite ends of the top or 85 cover, so as to receive the tongues on upper ends of the sides 3, and they serve to hold together the top and sides and to assist in securing the box-like compartments between the sides.

90 The base of the bookcase is designated by the numeral 8, which is formed at its front edge with an ornamental molding 9. It is provided at its opposite ends with the outwardly and upwardly extending metallic 95 plates 10, which form grooves 11 at opposite ends of the base, so as to receive the tongues or lower ends of the side members 3, and thus serve to assist in holding the base and side members together, as well as to secure the 100 box-like compartments in place.

The front edges of the side members 3 are provided with strips or moldings 12, which when the sides are in place will fit over the

front edges of the end members of the several box-like compartments, and thus conceal the meeting edges between the same and furnish an ornamental finish, recesses 13 being formed above the upper and lower ends of each of the strips or moldings 12, so as to receive the molding to the top or cover and the molding to the base, and thus form an ornamental finish, and also to assist in locking or securing the parts together at such points.

Under the construction described a very simple and efficient form of bookcase is provided, in which the several parts can be readily taken apart and placed in position when desired without the employment of nails or screws to hold the several parts together. When the bookcase is to be transported, the members are readily separated one from the other, and each compartment will continue to retain the books placed therein, so that they can be shipped without removal from the several compartments, thus very greatly reducing the labor attending the moving or shipment of the case and its contents and without injury or damage to the books.

I have illustrated and described with particularity the preferred details of construction and arrangement of the several parts; but it is obvious that various changes can be made therein without departing from the essential features of the invention.

Having described my invention and set forth its merits, what I claim is—

1. A bookcase composed of independent separable box-like compartments each having closed ends, back and open front and placed one upon the other so that the lower part of one will rest upon the upper part of the adjoining box with a horizontal portion between to form a shelf, separable side members having flanges adapted to lap over and conceal the joints between the side members and the ends of the compartments, a cover or top formed with grooves to receive the upper ends of the side members, and a base formed with grooves to receive the lower ends of said side members substantially as described.

2. A bookcase composed of independent separable box-like compartments each having closed ends, top, bottom and back and open

front and placed one upon the other so that the bottom of one will rest on the top of the adjoining box with the front meeting edges of the top and bottom flush with each other, a flange to the front edge of the horizontal side of each compartment adapted to fit over the front edge of the horizontal side of the adjoining compartment and conceal the joint between the compartments, separable side members formed with inwardly-projecting flanges along their front edges to conceal the joints between the side members and the ends of the compartments, a cover or top formed with grooves to receive the upper ends of the side members, and a base formed with grooves to receive the lower ends of the side members, substantially as and for the purposes described.

3. A bookcase composed of independent separable box-like compartments each having closed ends, top, bottom and back and open front, and placed one upon the other, a flange to the front edge of the horizontal side of each compartment adapted to fit over the front edge of the horizontal side of the adjoining compartment and conceal the joint between the compartments, separable side members formed with inwardly-projecting flanges along their front edges to conceal the joints between the side members and the ends of the compartments and with recesses at their upper and lower front edges, a cover or top formed with grooves to receive the upper ends of the side members and along its front edge with a depending flange to extend over the front top edge of the compartment below and into the recesses in the edge of the side members, and a base formed with grooves to receive the lower ends of the side members, and with an upwardly-projecting flange to extend over the front edge of the compartment next above and into the recesses in the lower edge of the side members, substantially as and for the purposes described.

In testimony whereof I affix my signature in presence of two witnesses.

WALLACE SUMNER GRANGE.
